COMBINED WELL PUMP AND MOTOR SUPPORT

Elmer E. Theis, Memphis, Tenn., assignor to Ace Pump Corporation, Memphis, Tenn., a corporation of Tennessee

Application August 20, 1948, Serial No. 148,197

Term of patent 14 years

(Cl. D65—1)

To all whom it may concern:

Be it known that I, Elmer E. Theis, a citizen of the United States, residing at Memphis, in the county of Shelby and State of Tennessee, have invented a new, original, and ornamental Design for a Combined Well Pump and Motor Support, of which the following is a specification, reference being had to the accompanying drawing, forming a part thereof.

Figure 1 is a perspective view of a combined well pump and motor support, showing my new design.

Figure 2 is an end elevation.

Figure 3 is an elevational view of the side opposite that shown in Figure 1.

I claim:

The ornamental design for a combined well pump and motor support, substantially as shown.
ELMER E. THEIS.
